CLAIM

The ornamental design for a wall plate as shown and described.

DESCRIPTION

FIG. 1 is a top, front, left perspective view of a first embodiment of a wall plate showing my new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a top, front, left perspective view of a second embodiment of the wall plate showing my new design;

FIG. 8 is a front view thereof;

FIG. 9 is a right side view thereof;

FIG. 10 is a left side view thereof;

FIG. 11 is a top view thereof; and,

FIG. 12 is a bottom view thereof.

The uneven-length broken lines immediately adjacent to the shaded area define the bounds of the claimed design and form no part thereof. The even-length broken lines illustrate portions of the wall plate that form no part of the claimed design.
